RECEPTACLE OF TEXTILE FABRIC AND
METHOD OF MAKING THE SAME

Leon J. Kraus, Philadelphia, Pa.

Application November 12, 1934, Serial No. 752,639

5 Claims.

(Cl. 150—1)

My invention relates to new and useful improvements in a receptacle of textile fabric and the method of making the same, which receptacle is adapted for use as a pillow cover, pillow case, hand bag or other article.

One of the objects of the invention is to produce a device of this character in which the obverse and reverse sides of the article will be of the same material and design.

Often it is impossible to obtain two sides of an article of this kind from a piece of fabric, due to the shape and size of such piece and if only one of the sides is obtainable there is considerable waste. Therefore another object of this invention is to fashion a piece of fabric into a plurality of sections of regular form with practically no waste and then secure said sections together in a manner that the two sides of an article are produced from the piece of fabric.

Another object of the invention is to assemble the sections so that a part of each forms a portion of both the obverse and reverse sides of the receptacle.

Another object of this invention is to produce an article of the kind mentioned by employing a certain method that is effective and that can be readily performed.

A further object of the invention is to use fabrics having a striped pattern or striped effect and to arrange the sections so that the stripes of one section are at an angle to the stripes of adjacent sections giving the appearance of the stripes of each section intercepting the stripes of contiguous sections, thus forming an attractive and pleasing effect to the eye.

A still further object of my invention is to produce an article of manufacture of unique construction in which the finished article is without a seam about the edge between the front and back sides. This reduces the amount of labor to make a device of the kind described over that necessary to construct an article of the same character in the regular way and which will have the obverse and reverse sides arranged as herein set forth.

With these and other objects in view, this invention consists of the details of construction and combination of elements hereinafter set forth and then specifically designated by the claims.

In order that those skilled in the art to which this invention appertains may understand how to make and use the same, I will describe its construction in detail, referring by numerals to the accompanying drawing, in which:

Fig. 1 is a perspective view of a receptacle in a

distended condition, constructed in accordance with my invention.

Fig. 2 is a face view of two sections stitched together with one section slightly turned back and illustrating one step in the course of manufacture, these two sections producing one-half of the article shown in Figs. 1 and 4.

Fig. 3 is a view similar to Fig. 2, showing the two sections which form the other half of the article illustrated.

Fig. 4 is a view of the receptacle wrong side out on a reduced scale and distended, with an opening left for turning the receptacle right side out, and

Fig. 5 is a perspective view of a modification. In carrying out my invention as embodied in Figs. 1 and 4, inclusive, I employ four sections 10, 11, 12 and 13 of striped textile fabric and by striped fabric I mean that which is woven with the stripes in it, or which has stripes printed thereon, or where the effect is produced by securing strips of fabric, braid or corded or other material to the foundation cloth. In other words, my invention contemplates the use of material which is actually striped or which has a striped effect and the terms used herein are to be so construed.

The four sections 10, 11, 12 and 13 are all true squares of exactly the same size and in the course of making a receptacle 14, the section 10 is superimposed on the section 11 with their right sides innermost or against each other and the stripes of one section are at right angles to the stripes of the other section. These sections are then secured together along two adjacent edges, as by stitches 15, which leaves section 10 with two free edges 16 and 17 and section 11 also with two free edges 18 and 19.

In a similar manner the section 12 is superimposed on the section 13 and they are secured together along two adjacent edges, as by stitches 20, which leaves section 12 with two free edges 21 and 22 while the section 13 has two free edges 23 and 24.

The two halves of the receptacle thus produced and illustrated in Figs. 2 and 3 now can be folded so that each half produces a right angle triangle in which the free edges of each section coincide and one of the free edges of each section aligns with a free edge of the other section to constitute the hypotenuse of the triangle. While thus folded, the edges 16 and 18 are secured to the edges 22 and 24 respectively and the edges 17 and 19 are attached to the edges 21 and 23 respectively, as by stitches 25. In one of the seams is left,

at least temporarily, an opening 26 whereby the article thus produced can be turned right side out to form the receptacle 14 having a border edge 27 without a seam, said border edge being created by the folds in the sections which, in the instance, are diagonals of the sections.

It is to be particularly noted that the seams of the finished receptacle extend diagonally and the strips of contiguous sections are arranged at angles to one another, the same being at right angle in the instant case.

In the modification illustrated in Fig. 5, each of the sections 28, 29, 30, 31, 32 and 33 are of diamond shape and four of these sections are arranged in pairs and secured together along two adjacent edges, then a third section is secured to one of the sections of each pair thus providing two complete halves. These halves are then folded on the short diameters of their respective sections and free edges of said halves secured together. The article thus formed is now turned right side out to complete the receptacle 34 in which each section provides a portion of the obverse and reverse sides of the receptacle, and the border edge 35 is created by the folds in the short diameters of the several sections and the stripes of contiguous sections run at angles to one another, being intercepted by the seams between such sections.

Of course I do not wish to be limited to the exact details of construction herein shown and described, as they may be varied within the limits of the appended claims without departing from the spirit of my invention.

Having thus fully described my invention, what I claim as new and useful is:—

1. In a device of the kind described, a plurality of rectilineal sections of striped textile material, each folded on a line between two of its corners to produce a triangle figure, and the edges of said sections secured together to form a receptacle in which the obverse and reverse sides thereof are identical and in which the border edge is without a seam.

2. In a device of the kind described a plurality of rectilineal sections of striped textile fabric hav-

ing their edges secured together so that the stripes of one section are at an angle to the stripes of contiguous sections and said sections folded on lines between corners common to each pair of adjacent sections whereby one part of each section forms a portion of the obverse side and another equal part forms a portion of the reverse side of a receptacle.

5

3. In a device of the kind described, a plurality of uniform square sections of striped material, each folded along a diagonal line and said sections secured together along their edges with the stripes of each section positioned at right angles to the stripes of contiguous sections, one-half of all of the sections forming the obverse side of a receptacle and the other half of all of said receptacle without a seam along the border edge.

10

4. In a device of the kind described, a plurality of uniform diamond shaped sections of striped material, each folded along its short diameter and said sections secured together along their edges with the stripes of each section positioned at angles to the stripes of contiguous sections, one-half of all of the sections forming the obverse side of a receptacle and the other half of all of said sections forming the reverse side of said receptacle without a seam along the border edge.

15

5. The method of producing a receptacle in which the obverse and reverse sides will be of the same material and pattern, the same being formed from a piece of striped textile fabric that cannot be cut into two areas equal to the dimensions of the sides of the receptacle; consisting of cutting the piece of fabric into uniform sections, then stitching the edges of a plurality of said sections together to form a half of the receptacle, then stitching the other sections together along their edges to form the other half of the receptacle, then folding the sections forming each half along lines between their corners and finally stitching the two halves together so that a border edge is provided without a seam and the stripes of each section are positioned at angles to the stripes of contiguous sections.
